UNITED STATES PATENT OFFICE.

JULIAN G. GOODHUE, OF CHICAGO, ILLINOIS.

DISINFECTING APPARATUS.

1,293,406.

Specification of Letters Patent.

Patented Feb. 4, 1919.

Application filed June 6, 1912, Serial No. 701,969. Renewed June 29, 1918. Serial No. 242,668.

To all whom it may concern:

Be it known that I, JULIAN G. GOODHUE, a citizen of the United States, residing at Chicago, in the county of Cook and State of Illinois, have invented a certain new and useful Improvement in Disinfecting Apparatus, of which the following is a full, clear, concise, and exact description, reference being had to the accompanying drawings, forming a part of this specification.

My invention relates to an improvement in disinfecting apparatus and has as its objects the provision of special apparatus for spraying disinfectant, which shall be more efficient, cheaper to manufacture and more easily assembled than is now the case.

A further object resides in the particular arrangement and combinations of parts hereinafter described.

Referring to the accompanying drawings, Figure 1 is a front elevation of one form of spraying or dispensing apparatus assembled, parts being broken away and partly in section;

Fig. 2 is a front elevation of a different type of apparatus, the reservoir parts being omitted;

Fig. 3 is a vertical sectional view on the central line of Fig. 2, showing my improved bracket arrangements, but also showing the reservoirs in place which are omitted in Fig. 2;

Fig. 4 is a horizontal cross section on the line 4—4 of Fig. 1, looking in the direction of the arrows;

Fig. 5 is a plan view partly in section of the special sprayer or atomizer shown in Fig. 2;

Fig. 6 is an elevational view showing the interiors of the two parts of the atomizer shown in Fig. 5;

Fig. 7 is a perspective view of a special fitting which may be used in assembling my apparatus; and

Fig. 8 is a perspective of another special fitting which may be used in my apparatus.

Referring more particularly to the drawings, 1 is a reservoir appearing in Figs. 1 and 4. Mounted above said reservoir 1 is a second reservoir 2. Reservoir 2 has a portion projecting within the reservoir 1 which terminates in a nozzle 3. The lower edge of this nozzle determines the liquid level in the reservoir 1 in a manner well known in dispensing apparatus. Member 1 is mounted directly on a bracket 4 which is made in two

parts 5 and 6. Part 5 is attached directly to the wall as by screws 7, while the part 6 is preferably hung from a secondary bracket 8, the member 8 being attached to the wall 60 by screws 9 and having wings or ears 10 which are bent away from the wall. The part 6 is provided with plate pieces 11 at its upper corners which are designed to fit flatly against the wall and drop into the 65 space between the ears 10 and the wall, thus supporting the weight of the part 6. The portions 11 may, however, be provided with screw holes for direct attachment to the wall, but the method described of using an 70 auxiliary bracket 8 is preferred on account of the ease with which the part 6 may be removed, and assembled and adjusted to the reservoir 2. The portions of parts 5 and 6 are generally rectangular in form, as shown, 75 and the part 5 has a floor or shelf 12 provided with a semi-circular ridge 13 which fits in a corresponding groove in the bottom of the reservoir 1, holding it securely in place. The part 6 is provided with portions 80 12' and 13' corresponding to 12 and 13 respectively on the part 5, except that the part 13' projects downwardly instead of upwardly. Parts 5 and 6 are also provided with horizontal members 14 and 15 uniting 85 with side pieces of the two parts. These horizontal members are provided with grooves 16—16 and 17—17, respectively, which are designed to permit the passage of tubes into the reservoir 1. The horizontal 90 members 14 and 15 also provide means whereby the parts 5 and 6 may be drawn forcibly together as by a bolt 18. Lugs 19—19 and 20—20 carried by parts 5 and 6 respectively, help to unite the two parts and 95 prevent lateral displacement at the point of junction. As best shown in Figs. 3 and 4, one of the upright pieces of the part 6 is provided with a recess 21. In installing the form of apparatus shown in Fig. 4, a special 100 fitting 22 is provided which has a right angled lug 23 for engaging one of the upright members of the part 6. A portion of this lug 23 is shown in Fig. 4 as lying in the recess 21 between the part 6 and the wall. As 105 also appears in Fig. 4, the recess 21 may accommodate a tube such as 24 for connecting the reservoir 1 with the spraying apparatus. As shown the member 22 has a bell shaped portion which receives the end of a pipe 25; 110 the other end of the pipe 25 is received by a special fitting 26. This fitting 26 also re-

ceives the end of a vertical pipe 27 and a second horizontal pipe 28. From the forward end of the pipe 28 an atomizer 29 may be suspended.

5 In assembling the apparatus shown in Figs. 1 and 4 a bracket of the type appearing in Figs. 2 and 3 is employed, and the reservoirs such as 1 and 2 are installed in the bracket, being held in place by engagement between the grooves in the members 1 and 2, and the ridges 13 and 13' on the parts 5 and 6 respectively.

The reservoir apparatus is provided with two tubes 30 and 31 for filling purposes, 15 which pass up through apertures 30' and 31' in the shelf 12 and through the grooves such as 16 and 17 in the bracket into a groove 32 in the wall of the reservoir 2, and thus down into the reservoir 1. In actual 20 practice the tubes used with the reservoir and spraying apparatus are arranged as shown in Fig. 4, but Fig. 1 shows them as spread apart for purposes of better illustration. The pipe 24 serves to convey liquid 25 from the reservoir 1 to the atomizing device 29. As shown in Fig. 1 the vertical pipe 27 incloses a tube 33 which leads from the door check or suitable source of compressed air, and delivers to the atomizer. It 30 will be obvious by referring to Fig. 7 that the member 50 illustrated in this figure may be substituted for the fitting 22. The fitting 50 would be used instead of the fitting 22 in any case in which it is necessary to run 35 the pipe such as 25 up or down before running it to the atomizer in order to avoid an obstruction. It would also be apparent that the member 51 may be substituted for 22 in any case in which the pipe 25 is omitted and 40 the tube 24 is run along the wall unprotected, since the member 51 is provided with a semi-circular outlet portion 52 which would 45 guide the tube 24 and protect it while passing beneath the bracket.

45 Referring more particularly to Figs. 2 and 3, it will be seen that it is unnecessary to mount the atomizing device at a distance from the reservoirs and bracket, but that a special form of atomizer such as 34 may be 50 installed in a position analogous to that occupied by fitting 22 in Figs. 1 and 4. The details of the special atomizing device 34 are best shown in Figs. 5 and 6. This atomizer 34 is made in two parts, 35 and 55 36. The part 35 is provided with two lugs 37 and 38 for hooking into the recess 21 as shown in Fig. 3, lug 38 also having a screw 39 for holding the device in place. The part 36 is provided with lugs 41—41 which help 60 to bind it to the part 35, both parts also being provided with identical lugs 42 and

43 for receiving a screw such as 44. The parts 35 and 36 are assembled as shown in Fig. 5 by inserting the lugs 40 and 41 into the aperture 45 in the parts 35 and then 65 fastening lugs 42 and 43 together by means of the screw 44. As shown in Figs. 2 and 6, the part 36 is provided with an aperture 46, through which the liquid may be sprayed. As will be apparent from the drawings, certain of the tubes necessary for the operation 70 of the spraying apparatus in Fig. 2 are indicated in dotted lines, but are shown fully in the aperture 46. It will be understood that glass receptacles are used in the interior of both forms of atomizer shown in the drawings, the parts shown and described being merely the exterior castings, the glass tube being necessary to retain the liquid. 75

Having thus described my invention, what I claim is:

1. The combination of a bracket having a reservoir apparatus supported thereon, said bracket having a recess in one of its side members, a fitting having a hook lying partly in said recess and engaging the side member of the bracket, a pipe connected to said fitting, a second fitting connected to the other end of said pipe, a second pipe supported from said second mentioned fitting, 85 an atomizing device suspended from one end of said second mentioned pipe, and a tube leading from said reservoir apparatus to said atomizer and passing through said recess, 90 said fittings and said pipes. 95

2. The combination of a reservoir apparatus comprising liquid holding vessels and a supporting frame therefor, disinfecting apparatus secured to and supported by 100 said frame, and pipes running from said vessels through the side of said frame and to the disinfecting apparatus.

3. The combination of reservoir apparatus comprising a liquid holding vessel and a metallic frame therefor, and an atomizer 105 having one end provided with a reservoir and the other end provided with means for attaching to said frame, and pipes extending from said vessel of the reservoir apparatus to the reservoir of said atomizer. 110

4. In combination, a separable reservoir apparatus, a frame supporting said apparatus, an atomizer operably connected to said reservoir and carried by the frame, and being removable with the frame and one 115 part of the separable reservoir.

In witness whereof, I hereunto subscribe my name this 22nd day of May, A. D., 1912.

JULIAN G. GOODHUE.
